SOUND CREATING DEVICE

Walter A. Garratt, Covington, Ky., assignor to
Philip G. Vondersmith, Covington, Ky.

Application July 2, 1948, Serial No. 36,712

11 Claims. (Cl. 116—137)

1

This invention relates to air operated warning devices or horns and is particularly directed to a horn of the type adapted for use on automobiles, bicycles, boats or vehicles of any sort for warning of the approach of the vehicle. The horn of this invention is inclusive of a valve and is of that type in which the sound is created by the rapid opening and closing of a valve, the vibratory motion of the valve being caused by means of air delivered under pressure.

The present improvements relate to structures of the type disclosed in the applicant's pending application, Serial No. 718,402, filed December 26, 1946, now U. S. Patent No. 2,492,740, and entitled "Sound Creating Device."

It has been the object of the present inventor to provide a horn construction of the character disclosed in the co-pending case in which the manufacture is greatly simplified and the horn assembled very quickly.

A further object has been to provide a plural tone horn in which the resonator parts include a vibrant disc of one piece appropriately placed between the resonator parts to provide the several orifices in proper relationship to the resonator chambers. The structure as disclosed is readily assembled within a casing and the parts appropriately adhesively attached or fused together.

It has been a still further object to provide a compact structure wherein the length of the inlet passages to the resonator chambers may be altered to secure a greater pitch range. The inlet passages are formed in the resonator body and thus are not extraneous parts such as tubing.

A further object has been to provide improved compact means for amplifying the sound.

A still further object has been to provide a horn of the above type which incorporates a valve seat formed of rubber or the like, wherein the valve seat functions without communicating vibrational force to the remainder of the structure which would most certainly occur if the valve seat were rigid. This permits all the energy, generated by the delivery of air under pressure, to be converted into sound, and accordingly, very little air pressure and very little volume are required.

Further objects relate to the arrangement of the air intake passageway through the unit to the compressible bulb as well as the appropriate valve which is incorporated in the vibrant disc and in the intake passage through which the air is drawn into the interior of the bulb for compression and delivery to the resonators.

Other objects and advantages of the invention

will be more fully apparent from a description of the accompanying drawings in which:

Figure 1 is a general view of the horn showing it partly in section so as to illustrate the general assembly of the parts.

Figure 2 is an exploded view showing the various parts of the horn.

Figure 3 is a front view of the resonator head.

Figure 4 is a front view of the resonator.

Figure 5 is an enlarged rear view of the sound creating unit, part of the casing being broken away for illustrating inlet passages for the resonator relative to the casing whereby the pitch of the horn may be varied.

Figure 6 is a view taken similar to Figure 5 showing the parts in a different position of adjustment.

Figure 7 is a face view of the rubber diaphragm or vibrant disc.

Figure 8 is a sectional view taken on line 8—8, Figure 5, illustrating the air intake control for the horn.

Figure 9 is a sectional view taken on line 9—9, Figure 8, illustrating the resonator construction in detail.

Figure 10 is a sectional view taken on line 10—10, Figure 1, detailing the clamp for the horn.

Generally speaking, the improved horn includes three principal parts or units, namely, a sound creating unit which is the basic part of the horn, means for supplying air to the sound creating unit, and means for projecting and amplifying the sound produced. These three primary parts or units may be referred to as the sound generator unit 10, a compressible rubber bulb 11, and a sound projecting chamber 12 which is also the frame structure. An attachment means is provided generally indicated at 13 and designed for attaching the horn, for example, to the handlebar 14 of a bicycle.

Described in detail, the main or basic unit, that is, the sound generator unit 10, consists of three main parts, the resonator body 15, the resonator head 16 and the casing 17 into which the first two parts are fitted. A vibrant disc 18 formed of rubber or some equivalent material is disposed between the resonator 15 and the resonator head 16. The parts 15 and 16 and the disc are held against rotative displacement by means of a dowel pin 19 projecting from one of the parts to the other through the vibrant disc. These three parts, that is, the resonator, the resonator head and the disc, are secured within the cup-shaped casing 17 by any suitable means such as adhesive. These parts, with the exception

tion of the vibrant disc, may be readily molded of plastic.

The parts 15 and 16 include aligned bores or passageways, these bores being indicated at 20 in the resonator and 21 in the resonator head. In the present disclosure, two of such passageways are disclosed although it will be apparent that a single one or a plurality may be used.

The present horn may be described as a two-tone horn. The air to the respective passageways is admitted through the closure end 22 of the casing through orifices 23 into channels 46, these orifices being diametrically opposite and disposed adjacent the cylindrical wall 24 of the casing.

The vibrant disc includes apertures 25, which apertures are co-axially disposed relative to the respective bores 20 and 21. The valves 26 are disposed in the passageways or bores 21 of the resonator head. They consist of cup-shaped metal caps or discs. Tubular amplifying elements 27 are provided and mounted in the bores 21 of the resonator head 16. The tubes or pipes provide for the first stage of amplification of the sound. The valves 26 are contained within counterbores 29 of the respective tubes. The external diameter of the valve is less than the internal diameter of the bore 29 so that the sound may pass around the valve outwardly through the tube when the valve is unseated.

The valve, in each case, is held against the vibrant disc over the aperture 25 thereof (Figure 9) by means of a coil spring 30 disposed under compression between the valve and a shoulder 31 at the inner end of the bore 29. The coil spring fits in the cupped end of the valve and accordingly, the flat closure end of the valve rests against the margin of the orifice 25 of the vibrant disc. As part of the bore 29 of the amplifying tube, a reduced bore portion 32 is provided and from this flares to the discharge end of the tube.

The resonator head 16 (Figure 3) includes a hub 34, the end of which is fashioned to form a three point cam 35. The amplifying tubes 27 contain as integral parts, segmental bearing points 37. To secure the slight tension required on the spring 30, the tube 27 is pushed firmly into the hub 34 until contact with the cam surfaces is made. A twist of several degrees will cause the tube to move in or out. Friction will hold the tube until the cement is applied. This operation is performed according to sound while the horn is being assembled and tuned. Some variation of pitch will occur with the change of spring tension, but the function of pitch range belongs to the adjustment provided for lengthening or shortening of the resonator channels 46 described later.

The rubber bulb 11 has its open end 38 engaged over the sound unit (Figure 1) including a sleeve portion 39 for this purpose. The sleeve portion includes shoulders 40 spaced apart internally of the sleeve the approximate width of the sound unit so as to be held therein against axial displacement. The bulb is spherical. Air is drawn into the bulb through a refill or intake passageway 41 extending through both the resonator head and the resonator (Figure 8) and through a bore 42 in the head end of the casing 17 which provides the entrance into the interior of the bulb.

The vibrant disc includes a flap type valve member 43 provided by making a circular cut in the disc and leaving a portion uncut. This flap

valve is free to move within the clearance afforded by a recess 44 in the face of the resonator adjacent the disc. The surface of the resonator is further relieved as at 45 to permit free flexing of the valve hinge portion, namely, adjacent the uncut part. The valve 43 is drawn to open position after the bulb is collapsed and released. Air under atmospheric pressure then rushes in through the passageway 41 to again fill up the bulb. When pressure is applied by compressing the bulb, the flap valve seats against the flush surface of the resonator head adjacent the aforesaid recess 44.

The air is supplied to the resonator as stated by compression of the rubber bulb. The air supply holes 23 are disposed adjacent to and enter grooves 46 formed in the rear face of the resonator body concentrically thereof. The outer ends of these grooves are closed as at 47 and the inner ends 48 curve toward the bores 20 to enter the bores tangentially. These grooves with the openings 23 constitute air passages, the effective lengths of which are varied for varying the pitch. The effect of rotating the assembly is to move the openings 23 along the grooves farther away from or closer to the bore 20. Thus the active length of the channels may be varied by this adjustment to procure the notes desired. These channels thus can have substantial length and effectively provide the length necessary to the procurement of notes in the desired ranges.

The back of the resonator includes a cavity as at 50 (Figure 8). This cavity connects the passageway 41 with the opening 42 in the back of the casing which admits the air to the bulb. Since the cavity 50 has substantial circumferential length and the openings 41 and 42 are disposed the same distance from the axis of the casing, air will pass through this common chamber as long as the rotative adjustment is within the limits of the cavity 50. A similar cavity 51, disposed diametrically opposite, conserves material.

In order to provide for the second stage of amplification, a thimble-shaped hood 53 is mounted over the amplifier tubes 27. This hood is inverted with respect to the tubes, that is to say, their outlets project the sound against the bottom 54 of the hood and the direction of the sound travel is reversed to pass out the rearwardly disposed open end 55 of the hood element. The hood element is conical in shape in order to permit the sound to spread out as it moves rearwardly away from the discharge ends of the amplifier tubes. The hood includes a centrally disposed partition 56 so that each amplifier tube projects into an independent chamber. This partition 56 projects beyond the open end of the hood element as at 57 and seats in a slot 58 provided between the hubs of the resonator head. An appropriate attachment is provided at this point, the hood, in this case, being plastic and the attachment being by means of some adhesive or fusion of the parts. This partition is notched as at 59 (Figure 8) to clear the entrance to the refill or intake passageway 41 into the bulb. The partition is beneficial although not strictly necessary.

The bell or sound projection casing 12 may be of plastic or metal. It includes a flared main portion 60 and a cylindrical bearing portion 61 which engages upon the exterior of the attachment portion of the rubber bulb 11. This element may include a flange 62 fitted to the spherical contour

of the rubber bulb. The outer end of the bell is further flared as at 63 for embellishment.

In order to provide for the continuous flow of sound, the inner end of the hood is thus sufficiently spaced from the sound unit as at 64 to permit an unrestricted flow out of the end of the hood and for reversal so as to be projected to the open end of the flared sound projecting chamber. Thus, the sound travels from the rubber disc through the amplifying tubes, reverses to pass out the rear end of the hood in a second stage of amplification and reverses again to pass out the forward end of the bell or sound projection chamber to provide the third stage of amplification.

In order to provide an added purpose for the horn, a reflective glass jewel or disc 65 is inserted in the forwardly disposed closed end of the hood and thus will pick up light thrown toward the horn as the vehicle is facing toward the source of light.

The horn is attached to the handlebar by means of the attachment means 13. The bracket 13 includes a split clamping means. The split clamping means includes upper and lower elements indicated at 70 and 71, respectively, and adapted to generally encircle the handlebar indicated at 14 (Figure 1). A pair of screws 72-72 with companion nuts 73-73 attach together the adjacent ends of the clamping elements. The upper clamping ring 70 includes a cupped disc 74 which engages and fits the underside of a circular lug 75 which is a part of the sound projection casing 12. This circular lug 75 has a rounded edge and nests in the cupped disc so as to rest within and rotate relative to the disc.

A split clamping ring, consisting of elements 76-76, encircles the lug 75 and the margin 77 of the cupped disc and holds these parts in rotative connection. The elements 76-76 have their adjacent ends joined by means of screws 78 and nuts 79 (Figure 10) for tightening the clamping elements to provide the proper frictional engagement between the cupped disc and the circular lug. Thus, the operator may rotatively adjust or swing the horn in a horizontal plane for properly directing it after it is placed on the handlebar.

In the operation of the device as the compressor bulb is squeezed, air under pressure passes through the apertures in the casing through the channels of variable length into the resonator through the passages 20 thereupon deflecting the suspended areas of the vibrant disc and finally unseating the valves to escape through the pipes or tubes as a musical note. As pointed out in the previous case, the suspended portion of a rubber disc bulges outwardly carrying the valve outwardly with it against the spring tension. However, the valve will not be unseated until the elastic properties of the disc reach a tension requiring greater pressure to continue than that necessary to unseat the valve. When this tension is reached, the valve breaks contact with the disc suddenly so that the escape of air is substantially explosive. These movements of the valve are in accord with the frequency represented by its musical note.

The vibration of the valve and the movements of the seat are produced with but very little pressure. The orifice tends to enlarge since the disc 70 has become convex but is restrained from doing so while engaged with the valve because of friction. When the valve lifts, the orifice snaps to a larger diameter. Because of its lighter weight and thus smaller inertia, the seat disc returns to

normal more rapidly than the valve. The projected energy is absorbed by the spring and returns the valve. However, since the return of the valve is later in the cycle than the return of the seat to its normal position, there is more clearance and, therefore, when the valve seats it does so squarely and with considerable impact. This impact energy being transferred to the rubber disc is converted by rebound to the reversal of the valve for the next cycle.

It is obvious, of course, that the valve assembly represents a definite weight. This fact must be included in all calculations. There are a number of factors which contribute or coordinate rhythmically to the creation of sound such as the pulsations of air set up under the disc as opposed to the acoustic loading which imparts an intermittent thrust on the outside of the disc, the two actions being one-half a cycle apart.

The whole purpose is to produce a series of minor explosions setting up a carrier wave of semi-musical quality upon which may be impressed resonance, harmonics and overtones. The result is an efficiently articulated musical note capable of wide variation in the manufacture. These variations are a result of alterations such as allowing the spring freedom to clatter, thus emitting the sound characteristics inherent in a tempered spring or mounting on the vibration valve a section of tuned wire.

It is a fact that a column of air under some compression is a vigorous conductor of sound, and by its very nature is extremely sensitive and will amplify a faint sound many times. A passage 35 plus a resonator bore form resonance of definite pitch. For example, the pitch may be varied from that represented by a short passage down to the longer extreme through which variation, a range of over an octave may be obtained. If a 40 still lower tone is desired, the valve may be made heavier and the same variations in passage used.

When applying air to operate the sounder, a coupling of much greater area than the resonators must be used—such as that of the bulb 11. The reason for this is that each of the two resonators is sympathetic to the vibration period represented by its own resonance. Therefore, if the sound unit is joined to a receptacle of greater dimensions and consequently different pitch, each resonator will isolate itself and remain harmonious. If it is desired to use a source of air from a long hose, it will still be necessary to interpose a container of at least one cubic inch between the air supply and the sounder. If this were not done, the air vibration set up in the sounder would tend to continue on down the supply hose and the formula would cease to exist. There may be sounds but so many variables would make it 55 pure chance; therefore, some such sonic filter should be specified.

One method to employ in describing this device is to consider that a jet of air is released during the period of one degree on the top peak of the sine curve, hence the phrase minute explosion.

With respect to pitch variation, it will be noted that the resonator bore 20, plus the channel 46, in each case, constitutes a resonator of calculated displacement area and, therefore, it will be constant in pitch. Rotating the casing and resonator relatively in one direction will cause a shortening of the active length of the air passage through the channel 46 resulting in a higher pitch, and by the same token, lengthening will lower the pitch. A range of several notes may be

obtained in this manner. A still further range may be secured by substituting valves of greater weight or by varying the thickness of the vibrant disc. Another variation, for instance, toward lower pitch would be to add thickness or weight to the vibrant disc around the valve aperture.

A heavier valve will produce slower pulsations, thereby allowing the resonator to close for longer intervals in each cycle, thus lowering the pitch. Conversely, if resonator capacity is reduced, the resulting higher pitch will compel the vibration timing to conform in sympathy. The volume of sound may be increased by using amplifying members of greater length than those disclosed.

Thus, it will be seen that a horn is provided in which the resonator means is designed for the input side of the horn. A column of air is vibrated thereby to produce notes of pitch consistent with the length or area of the resonator passages and amplification occurs on the output side of the unit.

Having described my invention, I claim:

1. A sound creating device comprising; a resonator, a resonator head, a vibrant disc formed of a sheet of rubber or the like secured between said resonator and resonator head, said resonator and resonator head including aligned openings constituting air passageways, said vibrant disc including openings co-axial with the aligned openings in the resonator and resonator head, air delivery channels formed within the resonator and communicating with the respective air passageways in the resonator, means for creating air flow through said air delivery channels, valve elements disposed against the margins of the respective openings in the vibrant disc on the side opposite to the side into which the air is delivered, means for urging said valve elements against the vibrant disc, amplifying tubes secured to said resonator head for continuing the air passageways therefrom, and means for individually adjusting the respective lengths of said tubes.

2. A sound creating device comprising; a resonator, a resonator head, a vibrant disc formed of a sheet of rubber or the like secured between said resonator and resonator head, said resonator and resonator head including aligned openings constituting air passageways, said vibrant disc including openings co-axial with the aligned openings in the resonator and resonator head, air delivery channels formed within the resonator and in communication with the respective air passageways within the resonator, means for adjusting simultaneously the effective lengths of said channels, means for creating air flow through said air delivering channels and said air passageways, valve elements disposed against the margins of the respective openings in the vibrant disc on the side of the vibrant disc opposite the resonator, spring means for urging said valve elements against the vibrant disc, and sound amplifying means secured to said resonator head.

3. A sound creating device comprising; a resonator, a resonator head, a vibrant disc formed of a sheet of rubber or the like secured between said resonator and resonator head, a casing consisting of a cup shaped member containing said resonator and resonator head, said resonator and resonator head including aligned openings constituting air passageways, said vibrant disc including openings co-axial with the aligned openings in the resonator and resonator head, air delivery passageways formed in the resonator and entering the air passageways in the resonator, said casing including inlet orifices for admitting air

5 to said air delivery passageways, means for creating air flow through said inlet orifices, valve elements disposed against the margins of the respective openings in the vibrant disc on the side of the vibrant disc opposite the resonator, and spring means for urging said valve elements against the vibrant disc.

4. A sound creating device comprising; a resonator, a resonator head, a vibrant disc formed of a sheet of rubber or the like secured between said resonator and resonator head, said resonator and resonator head including aligned openings constituting air passageways, said vibrant disc including openings co-axial with the aligned openings in the resonator and resonator head, air delivery passageways formed in the resonator and entering the air passageways in the resonator, means for creating air flow through said air delivery passageways, valve elements disposed against the margins of the respective openings in the vibrant disc on the side opposite the resonator, spring means for urging said valve elements against the vibrant disc, amplifying tubes secured to said resonator head for continuing the air passageways therefrom, means for adjusting the respective lengths of said tubes, an amplifier hood mounted over the tubes, and a sound projecting casing disposed about the hood.

5. In a sound creating device, a resonator including resonator passages, a vibrant disc disposed across the passages and including openings therein co-axial with the resonator passages but of smaller size, valves disposed against one side of said disc over said openings, means for delivering air through the disc from the other side thereof, amplifier tubes mounted on the resonator and extending the resonator passages to provide for sound amplification, and means for independently axially adjusting the amplifier tubes in order to vary the effective length of said tubes.

6. A sound creating device comprising; a resonator unit having a plurality of resonator chambers extended therethrough, a valve seat element mounted in said unit across said chambers, said valve seat element consisting of a disc of pliable material having a plurality of apertures therein, one for each resonator chamber, valve discs yieldably engaged against the outlet side of said valve seat element and engaging said seat element marginally of each of the respective apertures therein, and air delivery passageways entering said resonator unit on the side of said valve seat element opposite the valve discs, said air delivery passageways consisting of channels formed in the resonator unit.

7. In a sound creating device, a resonator including resonator passages, a vibrant disc disposed across the passages and including openings therein co-axial with the resonator passages but of smaller size, valves disposed against one side of said disc over said openings, means for delivering air through the disc from the other side thereof, amplifier tubes mounted on the resonator and extending the resonator passages to provide for sound amplification, said tubes being telescopically and rotatably engaged and including cam portions, said resonator including cam portions component to those of the tubes, whereby rotation of the tubes will vary the effective length of said tubes.

8. In a sound creating device, a resonator having resonator passages therethrough, a flexible vibrant disc having portions disposed across said passages and including openings disposed co-axially with the respective passageways, said

openings being of smaller diameter than the passageways, valve means in the respective passageways engaging the margins of the openings in the disc at the discharge side thereof, air delivery channels formed in the resonator and entering the input side of said resonator passages, said channels being of sufficient length to provide for variation in the pitch of the notes resulting as the air is delivered through the openings in the vibrant disc, means for adjusting and setting the length of said channels to procure the desired notes and, means for delivering air under pressure through said channels and through said resonator passages for delivering sound beyond the valves.

9. In a sound creating device, a pair of circular elements constituting parts of a resonator, a thin pliable disc interposed between said elements, said elements including a pair of aligned passageways therethrough parallel with the axis thereof, said disc including openings therein of small diameter than the diameters of the passageways whereby the margins of the openings in the disc are unsupported, valve means for the respective passageways controlling the openings in the discs, channels for delivering air to the passages at the side of the disc opposite to the valves, and means for adjusting simultaneously the effective lengths of the channels whereby the pitch of sound produced may be varied.

10. In a sound creating device, a resonator, a resonator head, a flexible vibrant disc interposed between the resonator and resonator head, said resonator and resonator head including aligned openings constituting air passageways, said disc including openings disposed co-axially with the respective air passageways, said openings being of smaller diameter than the air passageways, valve means mounted in the respective air passageways within the resonator head and engaging the

5

margins of the openings in the disc, air delivery channels formed within the resonator and communicating with the respective air passageways, means for adjusting simultaneously the effective lengths of the air delivery channels whereby the pitch of sounds produced may be raised or lowered, amplifier tubes mounted on the resonator head and leading from the respective air passages, and means for individually adjusting the effective lengths of the tubes whereby they may be tuned independently of one another.

11. In a sound creating device, a resonator, air passageways extending through the resonator, sound producing means within each of the air passageways responsive to air flow therethrough, air delivery channels formed within the resonator at one side thereof communicating with the respective air passageways, means for adjusting simultaneously the effective lengths of the air delivery channels whereby the pitch of sounds produced by the sound producing means may be varied, amplifier tubes mounted on the resonator at the side opposite the air delivery channels and leading from the respective air passageways, and means for individually adjusting the effective lengths of the tubes whereby they may be tuned independently of one another.
